UNITED STATES PATENT OFFICE.

HERBERT G. ISENBERG, OF JOHNSTOWN, PENNSYLVANIA, ASSIGNOR TO THE LORAIN STEEL COMPANY, OF JOHNSTOWN, PENNSYLVANIA, A CORPORATION OF PENNSYLVANIA.

SWITCH-TONGUE FASTENING.

1,074,365.

Specification of Letters Patent. Patented Sept. 30, 1913.

Application filed November 23, 1912. Serial No. 733,138.

To all whom it may concern:

Be it known that I, HERBERT G. ISENBERG, a citizen of the United States, and resident of Jamestown, in the county of 5 Cambria and State of Pennsylvania, have invented a new and useful Switch-Tongue Fastening, of which the following is a specification.

My invention has relation to the construction of switches, and more particularly to the construction of switches used on street railways, and the invention is designed to provide a switch having a new and useful arrangement of parts by the use 15 of which the switch tongue is pivoted and is held or maintained in its pivoted position on the body portion of the switch and whereby compensation for wear is automatically taken up and lost motion in the 20 moving parts prevented.

With this and other objects in view, as will appear hereinafter, my invention consists in the novel construction, arrangement and combination of parts whereby the 25 switch tongue is positioned and movably secured in place substantially as herein-after described and pointed out in the appended claims, reference being had to the accompanying drawings in which:

30 Figure 1 is a plan showing a portion of a switch structure embodying my invention. Fig. 2 is a side elevation on a larger scale, and partly in section, showing in detail the switch tongue and tongue fastening as constructed in accordance with my invention. Fig. 3 is a transverse section on a larger scale taken on the line III—III of Fig. 1. Fig. 4 is a sectional plan of the same, the section being taken on the line 40 IV—IV of Fig. 2.

In the drawings the numeral 2 designates the body of a switch structure having a movable tongue or switch point 3 pivotally secured by one end in place thereon so as to 45 permit the free end to swing in the usual known manner. The rear end or heel of the switch tongue is provided with a downwardly extending pivot pin 4 arranged to project into the opening or hole 5 provided for that purpose in the body portion of the switch structure. One side of the pivot pin 4 is cut away to provide a recess having a curved bottom surface 6 and having a depressed portion 7 therein the lower end 50 of the depression being made semi-circular

to form a seat for the swinging fastening bar 8 by which the pivot pin is locked within the pivot pin opening 5.

At one side of the opening 5 for the pivot pin 4 is a recess 9 which is formed in the body portion 2 of the switch to extend transversely and communicates with the interior of the box 10 which is located at one side of the switch and is provided with an open top normally closed by means of the 60 removable plate 11. The recess or slot 9 in the switch body, opposite the pivot pin opening 5, has a curved side wall 12 and a vertical depression or groove 13 is provided in the curved side wall 12. 70

The lower end of the fastening 8 is rounded so as to enter and fit the semi-circular seat 7 provided therefor in the bottom of the recess in the side of the pivot pin 4 and the outer swinging end of the 75 fastening 8 is arranged to engage with the curved side wall 12 in the recess 9 when the parts are assembled. A tongue 14 on the swinging end of the fastening bar 8 projects into the slot or groove 13 in the curved 80 side wall 12 so as to hold the bar 8 in position and the curvature of the side wall 12 is made eccentric to the radius defining the travel of the outer end of the fastening bar 8 when in position in its seat 7 in the pivot 85 pin 4, as will be more fully described hereinafter.

The parts being constructed as shown, the pivot pin 4 on the heel of the switch tongue 3 is inserted within the opening 5 90 provided therefor in the switch body 2 and, the cover plate 11 for the box 10 having been removed, the fastening bar 8 is inserted through the opening connecting the box 10 with the recess 9 until its lower end 95 is in engagement with the seat 7 therefor in the recess formed in one side of the pivot pin 4. The swinging outer end of the fastening 8 is then caused to swing forwardly or downwardly until in the position shown 100 in Fig. 2 and the outer end of this fastening 8 by engagement with the eccentrically curved side wall 12 of the recess 9 will wedge and hold the pivot pin in contact with the engaging surface of the opening 5 in the switch structure 2. The bottom 6 of the recess in the pivot pin being curved 105 permits the slight axially swinging movement of the pin in its seat necessary to allow the sidewise swinging movement of the 110

switch tongue. The fastening bar 8 when in such position will prevent the switch tongue 3 from lifting or being lifted from the switch body 2 until after the fastening bar 8 has been removed from its operative position in which its opposite ends engage with its seat 7 in the side of the pin 4 and the curved surface 12 within the recess 9. When, after continued use, the pivot pin 4 becomes worn or when for other reasons there is lost motion between the pivot pin and the opening 5 in which it is placed, the jarring of the cars passing over the switch will cause the outer swinging end of the fastening bar 8 to gradually fall downwardly and, as it is free to move by gravity, cause the fastening 8 to at all times hold the pin 4 tightly in engagement with the engaging surfaces of the opening 5 and in this way any lost motion between the pivot pin on the switch tongue and its seat in the switch structure will be taken up.

The advantages of my invention will be apparent to those skilled in the art. By means of my improved apparatus the swinging switch tongue is securely held in position in the body of the switch structure and compensation for wear is automatically effected so that lost motion in the joint between the switch tongue and its seat is prevented and overcome. The switch tongue is locked in position without the use of bolts or nuts while still readily detachable when required.

It will be obvious that various changes may be made in the details of construction and arrangement without departing from the spirit and scope of my invention as defined in and by the appended claims.

I claim:

1. In a railway switch a switch body having a pivot pin opening therein, a switch tongue having a pivot pin extending into said opening, registering recesses in adjacent faces of the pivot pin and pivot pin opening, and a tongue fastening comprising a locking bar loosely positioned within said registering recesses and arranged to secure the switch tongue in position on the switch body.

2. In a railway switch a switch body having a pivot pin opening therein, a switch tongue having a pivot pin extending into said opening, registering recesses in adjacent faces of the pivot pin and pivot pin opening, and a tongue fastening comprising a locking bar removably secured within said registering recesses and arranged to engage the opposite walls defining the depth of said recesses to secure the switch tongue in position on the switch body, said switch body

having a transverse recess communicating with the registering recesses through which the removably locking bar is inserted and removed.

3. In a railway switch a switch body having a pivot pin opening therein, a switch tongue having a pivot pin extending into said opening, registering recesses in adjacent faces of the pivot pin and pivot pin opening, and a tongue fastening comprising a locking bar positioned within said recesses, the ends of said bar engaging with the walls defining the depth of said recesses to secure the pivot pin in position in the pivot pin opening.

4. In a railway switch a switch body having a pivot pin opening therein, a switch tongue having a pivot pin extending into said opening, registering recesses in adjacent faces of the pivot pin and pivot pin opening, and a tongue fastening comprising a locking bar within the recesses, the ends of said bar engaging with the walls of the recesses to prevent removal of the switch tongue from the switch body, and the wall of the recesses in the switch body engaging with the pin being curved to wedge the bar in locking position.

5. In a railway switch a switch body having a pivot pin opening therein, a switch tongue having a pivot pin extending into said opening, and a tongue fastening within said recesses, the ends of said bar engaging with the walls of the recesses to prevent disengagement of the switch tongue and switch body, registering recesses in adjacent faces of the pivot pin opening, the side wall of the recess in said switch body engaging with the locking bar being curved to wedge the bar in locking position and having a groove to receive the tongue on the end of said locking bar.

6. In a railway switch a switch body having a pivot pin opening therein, a switch tongue having a pivot pin extending into said opening, registering recesses in adjacent faces of the pivot pin and pivot pin opening, and a tongue fastening comprising a pivoted locking bar within the recesses, the side wall of the recess in the switch tongue body being curved eccentrically to the path of swinging movement of the free end of the locking bar to wedge the bar in position and hold the switch tongue in place on the switch body.

In testimony whereof, I have hereunto set my hand.

HERBERT G. ISENBERG.
